NECKTIE AND LINING THEREFOR

Rudolph De Socarras, Passaic, N. J., assignor to
 Botany Worsted Mills, Passaic, N. J., a corporation of New Jersey

Application February 8, 1934, Serial No. 710,241

1 Claim. (Cl. 2—146)

This invention relates to neckties, particularly four-in-hand neckties comprising an outer fabric covering or casing a compound lining.

The object of this invention is to produce a necktie which is substantially rigid or non-stretchable in a lengthwise direction and the lining whereof in the direction angular to the length of the tie, is provided with sufficient flexibility or resiliency, particularly in the portions 10 of the tie constituting the knot, as to permit draping of the tie without wrinkling and which lining has the tendency to restore itself and the tie casing to a substantially flat condition when the tie is unknotted.

15 A further object of this invention is to provide a necktie, of which the compound lining is cut to substantially the size and configuration which the tie is to assume and which compound lining constitutes the body of the tie, the casing, having substantially the same shape and configuration 20 of the lining, provides a decorative covering for the lining, and the compound lining by reason of its unique construction supports the casing throughout its entire length and width, insures 25 the casing against lengthwise stretch and disfigurement, permits draping particularly of the knot portion of the tie without wrinkling or creasing and tends to restore the casing and itself to a substantially flat condition when the 30 tie is not knotted.

A particular embodiment of my invention is illustrated in the accompanying drawing in which Fig. 1 is an inner face view of the linings secured together by stitching forming a unitary 35 construction of my invention; Fig. 2 is an inner face view of a necktie of the four-in-hand type showing an embodiment of my invention; Fig. 3 is a front view of my improved interlining showing its relative relation when made up in the 40 form of a knot; Fig. 4 is a front view of the completed tie embodying my invention made in the form of a four-in-hand knot, and Fig. 5 is a detail cross-section taken on the line 5—5 of Fig. 2.

45 The body material or casing of the tie may be made of any suitable material such as wool, silk or other suitable fabric. The casing of the tie is so folded as to form a narrow intermediate neck portion 10, a narrow end 11, and a wider end 12. The casing edges are so formed on their inner faces as to overlap one another, providing a seam 13 held together by stitching 14. The interlining of the tie to which my invention particularly relates consists of a com- 50 pound lining comprising the main lining 15 and

a narrow reinforcing strip 16. The main lining 15 and the narrow reinforcing strip 16 are both made from flexible resilient material known commercially as "resilin." The main lining 15 is, however, cut on the bias thereby exposing on the said edges of the main lining the loose ends of both the warp and the weft threads in contradistinction to cutting the material straight which exposes only the loose ends of the weft threads on the side edges of the material. The 10 reinforcing strip 16 is cut straight exposing only the loose ends of the weft threads at the side edges of the strip. The neck portion 17 of the main lining and the neck portion 18 of the reinforcing strip are substantially of the same width 15 and the reinforcing strip 16 is of substantially the same length as the main lining 15 as shown in Fig. 1, in order that the reinforcing strip should extend from end to end of the main lining. The main lining 15 and the reinforcing 20 strip 16 are secured together by a single row of lengthwise stitching 19 running substantially centrally of the reinforcing strip, leaving the side edges of the reinforcing strip loose or unattached. The main lining, beginning at the portion thereof 25 which is utilized in forming the knot of the tie, is wider than the reinforcing strip and the loose ends of the bias cut material of the main lining are not in engagement at this section with the reinforcing strip.

30 The casing when the tie is completed is of substantially the same size and configuration as the compound lining, as is illustrated by the dotted lines 20 of Fig. 2. In Fig. 3 the combined main lining and reinforcing strip are shown 35 without the outer casing thereon, tied as a four-in-hand tie in order to show the relative relation of the parts thereof. The complete tie, tied as a four-in-hand tie, is shown in Fig. 4. The lower portions on the inner face at both ends of the tie to substantially the transverse broken lines shown in Fig. 2, thereby covering the lower portions of the interlining.

45 It is to be noted from the foregoing description that the tie is rigid or non-stretchable in a lengthwise direction and that the neck portions of both linings are of equal width, the neck portion of the bias cut main lining being reinforced 50 throughout its length and along the edges thereof by the corresponding portion of the reinforcing strip. The portion of the main lining which goes into the knot is slightly wider and gradually tapers outwardly with respect to the neck por- 55

tion, the bias cut material at the knot portions of the tie being unsupported by the reinforcing strip and consequently these portions and particularly the loose ends of the bias cut material 5 may readily flex in the direction in which they are forced when the tie is knotted. These threads, being inherently flexible and resilient, will consequently arch or bend when the tie is knotted, and will support the casing as the casing 10 assumes the same shape as the compound lining, resulting in proper draping of the tie. The arched or bent threads of the main lining when the tie is unknotted, assume a flat condition and thereby flatten out the casing to substantially 15 its original shape.

15 I claim:

20 A neckties comprising a compound lining consisting of a main lining of woven textile material cut on the bias so as normally to be resilient in longitudinal and transverse directions, said main lining being of the same length and shape as

that of the tie and extending from end to end of the tie, a woven reinforcing strip cut straight and substantially non-resilient in longitudinal directions, said reinforcing strip being of the same length as the main lining and being sewn to the main lining by a single row of stitches extending substantially centrally of the main lining and from end to end of the reinforcing strip, said stitching uniting said linings to form a unitary compound interlining non-stretchable in length- 10 wise direction, said main lining and said reinforcing strip being unhemmed, the threads of said main lining being angularly disposed with respect to the cross threads of said reinforcing strip, the ends of the threads of the main lining 15 being loose and freely movable, a casing enclosing said compound lining, said casing having substantially the same shape and configuration as the main lining.
